UNITED STATES PATENT OFFICE.

CHARLES H. MILLER, OF ERIE, PENNSYLVANIA.

COMBINED DOOR-CATCH AND DOOR-OPENING DEVICE.

SPECIFICATION forming part of Letters Patent No. 363,666, dated May 24, 1887.

Application filed March 26, 1886. Serial No. 196,737. (No model.)

To all whom it may concern:

Be it known that I, CHARLES H. MILLER, a citizen of the United States, residing at Erie, in the county of Erie and State of Pennsylvania, 5 have invented certain new and useful Improvements in Combined Door-Catch and Door-Opening Devices; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in combined door-catch and door-opening devices; and it consists in the improvements hereinafter set forth and explained.

20 My invention is illustrated in the accompanying drawings, in which—

Figure 1 is a perspective view of a section of a stove and stove-door with my improved catch and door-opening device thereon. Fig. 2 is a vertical end section of the same on the 25 line *y y* in Fig. 1, looking in the direction of the arrow *y*. Fig. 3 is a vertical end section of the same on the line *x x* in Fig. 1, looking in the direction of the arrow *x*.

Like letters refer to like parts in all the 30 figures.

In the drawings, A is a section of the side of a stove, and B an ordinary stove-door, having a latch, C, thereon of ordinary and usual construction. Directly under the point where the 35 latch C meets the frame I cast upon the frame A, or otherwise secure thereto, a lug, D, which projects outwardly from the frame A, so that the latch C will pass over it, the end of this lug D being provided with a notch, *d*, for the 40 purpose hereinafter explained. To this lug D I hinge a lever, E, by means of a pintle, *e*, the end of this lever E extending into a recess, F, in the frame A, where it curves upward at *f* behind the latch C, when the door B is closed 45 against the face of the frame A. To the lever E, I hinge a dog or catch, G, by means of a pintle, *g*, this dog or catch G being hinged to the lever E at a point beyond the end of the lug D on the frame A. On the inner edge of 50 the dog or catch G, I make a tooth or cog, *g*², which operates in the notch *d*, hereinbefore referred to, in the end of the lug D. The up-

per side, *g*³, of the dog or catch G is made of such shape that when the door is closed it rests upon or extends over the top of the lug D until 55 the end *g*⁴ reaches the outside of the latch C, as illustrated in Figs. 1 and 2, retaining the latch C against the face of the frame A. When, however, it is desired to open the door B, the outer end, H, of the lever E is pressed downward, as illustrated in Fig. 3, which raises the point *g*⁴ of the dog G, and at the same time turning it backward by the operation of the cog *g*² in the notch *d* in the lug D, (thereby releasing the latch C) and turning it out of the 60 way, so that the latch C will pass freely over the end *g*⁴ of the dog or catch G, the curved end *f* on the lever E operating simultaneously therewith to force the latch C outward, thereby unlatching and forcing the door open at one 65 operation.

In Fig. 3 I have illustrated in dotted lines different positions of the parts of the mechanism of my improved door-catch and door-opener, the dotted line E' showing the position of the 75 mechanism when the door is closed and secured, the full lines E showing the same as it appears when the door is fully released, and the dotted lines E² showing the lever pressed down as it is in the operation of throwing the 80 door open.

It will be observed that my device operates to latch and unlatch, and at the same time open the door without in anywise lifting the door B, it at all times swinging freely on its 85 hinges I I, with its entire weight resting thereon.

I have thus shown a convenient form of mechanism for utilizing my invention; but the same may be varied both in form and arrangement of parts—for example, it might be placed 90 at the under edge of the door and operate in contact with the lower edge thereof, instead of with a latch on the side of the door, as shown in the drawings, and good results obtained without departing from the spirit of my invention. Therefore I do not desire to limit myself 95 to the exact form of mechanism shown.

Having thus fully described my invention, so as to enable others skilled in the art to which it appertains to construct and use the 100 same, what I claim as new, and desire to secure by Letters Patent of the United States, is—

1. The combination, in a door-catch and door-opening device, of a door-frame having a pro-

jecting lug thereon, a lever pivoted to said lug, and a dog pivoted to said lever, with a door having thereon a catch closing over the lug on the door-frame, substantially as and for the purpose set forth.

5. 2. In a door-catch and door-opening device, the combination of a door-frame having a projecting lug thereon, and a recess at one side of said lug, a lever pivoted to said lug, and a dog pivoted to said lever, with a door provided with a catch closing over the lug on the door-frame, substantially as and for the purpose set forth.

10. 3. The combination, in a door-catch and door-opening device, of a door-frame provided with a projecting lug having a notch in the end thereof, a recess at one side of said lug, a lever pivoted to one side of said lug, one end of which lever extends into said recess and the other 15 outwardly beyond said lug, and a dog pivoted to said lever, having a projection thereon oper-

ating in the notch in the said lug, with a door hinged to said door-frame provided with a catch closing over said lug on the door-frame, substantially as and for the purpose set forth. 25

4. The combination, with a stove-door frame, A, having recesses F therein, and the lug D, provided with a notch, d, in the end thereof, and the door B, having the latch C thereon, of the lever E, pivoted to the lug D by the pintle e, 30 and having the curved end f, extending into the recess F, and the dog or catch G, pivoted to the lever E, and having the cog g, intermeshing with the notch d in the end of the lug D, all constructed and operating substantially 35 as and for the purpose set forth.

In testimony whereof I affix my signature in presence of two witnesses.

CHARLES H. MILLER.
